CLAIM

I claim the ornamental design for a hook retriever device, as shown and described.

DESCRIPTION

FIG. 1 is perspective view of a hook retriever device showing my new design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

The broken lines in FIG. 1 illustrate environment only and form no part of the claimed design.
